UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,504, dated October 4, 1881.

Application filed August 9, 1881. Term of patent 3½ years.

To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a large rectangle containing a large bouquet, B. Half of these figures A and B is shown at the upper and half at the lower part of the photograph. In one upper corner of the figure A is a circular figure, C, decorated with inner smaller circular figures. In the other upper corner of the figure A is a star-shaped figure, D. The top of the figure A is castellated in appearance, as shown by the stripe a. Above this stripe a is another figure, E, containing a floral ornament, b, on a decorated background, d. In the upper part of the figure E is an inclined stripe, e, having V-shaped bend. In the upper corners of the figure E are rosettes f and g. Between the figures C, E, and g starts a pentagonal figure,

F, containing bouquet h. A broad band, i, separates the figure F from figures E and g. 30 Above the figure F is another rectangle, G, containing a bouquet, j, and below said bouquet a diagonal stripe, K, which is ornamented with rosettes and other decorations. In the photograph part of figure F is shown at the right-hand side, part in the upper and the remainder in the lower left-hand corner. Likewise figure G is shown partly on the left, partly in the upper and partly in the lower right-hand corner. 35

The order in which the above-mentioned figures are arranged relatively to each other may be varied without materially varying the character of the design.

I claim—

1. The design for carpets, consisting of the figure C, substantially as shown.
2. The design for carpets, consisting of the figure D, substantially as shown.
3. The design for carpets, consisting of the figures A B C D E F G a b d e f g h i j K, substantially as shown. 50

HENRY HUNT.
